UNITED STATES PATENT OFFICE.

EDMUND GOLUCKE, OF CRAWFORDVILLE, GEORGIA.

DESIGN FOR A BED-RAIL FASTENER.

SPECIFICATION forming part of Design No. 27,533, dated August 17, 1897.

Application filed June 24, 1897. Serial No. 642,198. Term of patent 14 years.

To all whom it may concern:

Be it known that I, EDMUND GOLUCKE, a citizen of the United States, residing at Crawfordville, in the county of Taliaferro and State 5 of Georgia, have invented and produced a certain new and original Design for Bedstead-Rail Fasteners; and I do declare the following to be a full, clear, and exact description of the invention, such as will enable others skilled 10 in the art to which it appertains to make and use the same.

My invention relates to a design for a bed-rail fastener.

It relates to the entire configuration of the 15 fastener and especially to a fastener made of malleable iron or steel.

My invention relates particularly to the bed-rail fastener as illustrated in the accompanying drawing, in which the figure is a perspective view of a bed-rail fastener embodying 20 my design.

The leading features of my design appear in the following description:

1 represents an approximately rectangular 25 plate formed with countersunk orifices 2 2

and cylindrical projecting studs 3 3 on its opposite plane faces. 4 represents the front edge of said plate, and 5 represents a cylindrical stud projecting from the upper edge thereof in the same plane as the plate and at 30 an angle of about forty-five degrees to the line of the front edge 4.

6 represents a tapering stud projecting from the lower edge in the same plane as the plate at an angle of about forty-five degrees to the 35 front edge of the plate and parallel with the stud 5.

Having thus fully described my invention, what I claim as new and useful, and desire to secure by Design Letters Patent of the United 40 States, is—

The design for a bed-rail fastener, substantially as herein shown and described.

In testimony whereof I hereunto affix my signature in presence of two witnesses.

EDMUND GOLUCKE.
